UNITED STATES PATENT OFFICE.

ROBERT SPEIDEL, OF CALMBACH, NEAR WILDBAD, GERMANY.

REFRIGERATOR.

Application filed May 15, 1922. Serial No. 561,074.

To all whom it may concern:

Be it known that I, ROBERT SPEIDEL, a citizen of Germany, residing at Calmbach, near Wildbad, Germany, have invented a certain new and useful Refrigerator; and I do hereby declare the following to be a full, clear, and exact description of the invention, of which the following is a specification.

The known ice boxes and cold storage rooms have the disadvantage that the goods stored therein such as meat and nutriments commence in many cases after a period of 24 hours to assume a bad appearance and an unpleasant smell and also to decompose. This is caused by insufficient airing. The air is directly admitted through a small number of little holes. A sufficient airing is not possible with the direct air supply, as in such a case the temperature in the interior of the ice box would become too high and the ice would melt too quickly. Further with the direct air supply the bacteria causing decay get to the nutriments so that preserving for a longer period is not possible.

The object of the present invention is to provide a refrigerator which will be characterized by a small consumption of ice and in which the goods to be preserved can be kept fresh for weeks even in midsummer.

According to the invention this object is achieved by admitting to the space for storing the goods sufficient quantities of fresh air which has been previously cooled. Preferably the admission of air is effected by means of a cooled air filter.

With a refrigerator of this character provisions have been made for a sufficient airing of the goods and the decay-producing bacteria can be retained in the filter so that they cannot reach the meat or the like. In addition thereto the refrigerator has the advantage of being economic, as the consumption of ice is small even in hot climates and is a fraction of the amount heretofore required for this purpose and it insures the presence of fresh air free from germs.

The refrigerator is characterized by the following advantages:

- 50 1. The keeping of the goods such as meat and the like for weeks.
2. The preserving of the goods without loss of weight, nutrition and taste and thus has the advantage of being very economic.

3. A drying of the goods, as, for instance, when admitting cold drying air and the loss of weight which means a loss of money cannot occur with the refrigerator.

4. A preserving of the meat or the like for a considerable period required heretofore a storing in the cold storage room at temperatures below 0 degree centigrade. This was followed by a great loss of the amount of albumin, the most precious nutrient which coagulates when freezing.

This great disadvantage is avoided with the present process even when storing the goods for weeks, as the goods brought into the cold storage rooms are only kept cool and not frozen without being subjected to any decomposition.

In the accompanying drawing in which one mode of construction of the cooling reservoir for carrying out the new process is illustrated by way of example.

Fig. 1 is a vertical section through the reservoir along the line A—B of Fig. 3,

Fig. 2 is a vertical section along the line E—F of Fig. 3,

Fig. 3 is a horizontal section along the line C—D of Fig. 1,

Fig. 4 is the vertical section of the lower filter on a larger scale, and

Fig. 5 is the vertical section of the upper filter also on a larger scale.

The cooling reservoir consists chiefly of the outer wooden casing *a*, the walls of which are covered with suitable insulating material for instance with cork plates or the like or alternately with layers of leather *b*, card board *b* and layers of felt or similar material *c*. The inner surface of the walls is covered with sheet iron *d* (Fig. 5).

In the interior of the wooden casing is a second casing *e* of sheet iron. The lid *f* of this casing can be made after the style of an arch as it is intended to carry the ice. The side walls of the casing are provided with ribs running horizontally and strengthened by means of iron rods *g* having recesses and a T-shaped cross section and running vertically. The ribs have a triangular cross section as may be seen from Fig. 5, in which case the upper surface of the ribs runs horizontally. The ribs serve a double purpose, first for increasing the cooling surface and second for inserting trays for instance of sheet metal for the

goods, which trays are provided with openings (holes, slots or the like) in order to enable the air to pass all around the goods.

Above the bottom *i* of the ice box supporting ledges *k* are arranged for carrying a frame *l*. Above the supporting ledges *k* extends the sheet metal lining *d*. The frame *l*, for making a tight fitting is provided with a chamfered outer surface matching the supporting ledges *k* covered with a packing material such as rubber or cork plates *m*. To the under surface of the frame *l* a wire netting *n* is fastened. The wire netting is bordered with a U-shaped and bent metal strip *o*, to which a flat metal strip *p* has been soldered. The metal strip *p* is nailed to the under surface of the frame *l* or screwed thereto. It serves at the same time for fastening the lower end of the rubber packing *m*. The upper end of the rubber packing *m* is held by means of the metal strip *q*.

On the wire netting *n* is placed a porous insulating material *r*. In this case preferably wood shavings are used, as they are cheap and very suitable for the present purpose. The wood shavings may be saturated with an odourless and germ-killing substance. Above the insulating material *r* a second wire netting *s* is arranged which is covered by a grate *t*. The wire nettings hold the insulating material together without obstructing the passing of the air. The grate *t* consists preferably of perforated sheet iron. It is together with the wire netting *s* connected to an auxiliary frame *u* which preferably has an angular cross section and which fits accurately into the main frame *l*. The size of the grate *t* has been so chosen that it covers the joint between the frame *l* and the supporting ledges *k*. The rim of the grate *t* has no perforations. In order to permit an easy removal of the grate *t* it is fitted with rings *v*. In order to hold the grate in its position clamping means or the like can be arranged on the ledges *k*.

The bottom *i* of the box is provided with openings *w*. These are preferably arranged in such a manner that every one of the openings *w* lies vertically beneath a hole *x* of the grate *t*.

Underneath the bottom *i* of the ice box is arranged a flat open vessel *y* preferably of sheet iron for catching the ice water passing through the openings *w*. The vessel *y* is removably supported on ledges *z* and preferably arranged on an incline so that the accumulated water can be drained at the front end into another vessel.

At the upper end of the inner casing *e*, *f* one or more devices are arranged for the passage of air. These consist also chiefly of a porous insulating material arranged between two wire nettings. For holding

the insulating material I have shown in the drawings a tray *1* which is made tight with reference to the outer wall *a* of the box by means of a flanged packing ring *2*. To the inner wall *e* the tray is fastened from the inside by means of a flange *3*. The fastening is preferably effected by means of soldering. In the interior of the tray close to the end a ring *4* of angular cross section is fastened preferably by soldering. This ring supports a wire netting *5* bordered by a U-shaped bent sheet iron ring *6*. The ring *6* is by means of a perforated lid *7* pressed against the ring *4*. The ring *6* is fastened to the flange *3* preferably by soldering.

Into the outer end of the tray *1* a ring having a Z-shaped cross section is placed. The outer flange *8* of this ring exerts a pressure on the flange of the packing *2*. Against the inner flange *9* bears the outer wire netting *10* which is also bordered by a U-shaped bent sheet iron ring *11*. The sheet iron ring *11* is held by means of the perforated lid *12* which is screwed to the outer wall *a*. Above the lid *12* a further lid *13* is arranged which serves for a partial or full closing of the openings of the lid *12* in order to be able to regulate at will the circulation of the air.

The porous insulating material *14* is arranged between the two wire nettings *5* and *10*.

Above the tray *1* a perforated sheet iron *15* is resting on corresponding ledges *16* and *17*. It can be fastened on the one side by means of hinges. The sheet iron *15* serves as a protection for the tray *1* that it cannot become damaged by pieces of ice while at the same time it carries a portion of the upper ice masses.

The insulating material of the bottom need not all be porous. A series of single tubes or the like can be placed into the bottom which in a similar manner as the trays *1* receive the air filter.

The cooling box acts in the following manner:

If the box be used, the bottom part above the grate *t* is filled with ice and in the same manner ice is placed on top of the lid *f*. At first the air and the goods within the box have the temperature of the atmosphere. In consequence of the ice having been placed within the box the temperature falls very rapidly. The air therefore contracts and through the upper air filter *14* air is drawn in from the outside. A downwardly directed air current is thereby produced within the box. The air flows out at the bottom end through the filter *r*. Through this filter the water also passes out.

The air filter *14* is cooled by the water from the ice on top of the lid *f* so that always only cooled air can enter the interior

of the ice box. The bacteria contained in the air and which could cause a decaying of the goods stored in the ice box are retained by the filter and prevented from passing 5 into the interior of the refrigerator.

From time to time the filter masses especially those of the bottom filter must be renewed which can be easily and quickly effected.

10 Experiments have proved that with the use of the new refrigerator, meat can be kept fresh in mid summer for a period of from 3 to 4 weeks without loss of weight or albumin.

15 The upper layer of ice may under certain circumstances be omitted.

The invention is not only suitable for stationary cooling installations but it can also be applied with advantage to railway

20 carriages, ships and the like.

I claim as my invention:

1. A refrigerator consisting of a vessel fitted on the upper and on the lower end with ice cooled filters to maintain a uniform 25 temperature in the vessel, the filter masses being held between porous and resistable plates, the plates of the lower filter being carried by a frame arranged in a tight manner above the bottom of the vessel, the 30 upper porous plate of said lower filter being covered by a grate for conducting the ice water, the grate consisting of perforated sheet metal, the unperforated rim-parts of said sheet metal covering the joints between 35 the frame and its supporting ledges.

2. A refrigerator consisting of a vessel fitted on the upper and the lower end with cooled filters, the filter masses being held between two porous and resistable plates, 40 the upper porous plate of the lower filter being fastened together with a grate arranged above said plate to an auxiliary frame which is removably inserted into the main frame.

45 3. A refrigerator consisting of a vessel fitted on the upper and the lower end with cooled filters, the filter masses being held between two porous and resistable plates, the porous and resistable plates of the upper 50 filter being arranged on the ends of a tray extending between the inner sheet metal cover of the box and the outer wall, the tray being tightened with regard to the outer wall by means of a flanged packing 55 ring and being fastened from the inside to the inner wall by means of a flange.

4. A refrigerator consisting of a vessel fitted on the upper and the lower end with cooled filters, the filter masses being held 60 between two porous and resistable plates, the porous and resistable plates of the upper filter being arranged on the ends of a tray extending between the inner sheet metal cover of the box and the outer wall, the 65 inner porous and resistable plate being

bordered with a U-shaped bent sheet metal strip and being held between a ring fastened to the tray and a perforated lid fixed to the flange of the tray.

5. A refrigerator consisting of a vessel 70 fitted on the upper and the lower end with cooled filters, the filter masses being held between two porous and resistable plates, the porous and resistable plates of the upper filter being arranged on the ends of a tray 75 extending between the inner sheet metal cover of the box and the outer wall, the outer porous and resistable plate being bordered with a sheet metal ring and being held between a perforated sheet of iron detachably fastened to the outer wall and a ring of a Z-shaped cross section, the outer flange of said Z-shaped ring resting on the flange of the packing ring.

6. A refrigerator consisting of a vessel 85 fitted on the upper and the lower end with cooled filters, the filter masses being held between two porous and resistable plates, the porous and resistable plates of the upper filter being arranged on the ends of a tray 90 extending between the inner sheet metal cover of the box and the outer wall, a perforated sheet metal plate being arranged above the plate for protecting it.

7. A refrigerator for preserving nutrients and other goods, consisting of a vessel fitted on the upper end and on the lower end with ice cooled filters, the bottom of the vessel being perforated and the lower filter resting on the perforated bottom with ice 95 on the lower filter whereby the ice at the lower end of the vessel co-acts with the ice in the upper portion of the vessel to maintain a uniform temperature and thereby prevent the entry of and ascendency of 100 warm air upwardly into the vessel through the perforated bottom to counteract the downward current of air and whereby the constant downward current of air through the vessel is maintained and the ice maintained out of contact with warm air.

8. A refrigerator for preserving nutrients and other goods, consisting of a vessel fitted on the upper end and on the lower end with ice cooled filters, the bottom of the vessel being perforated and the lower filter resting on the perforated bottom with ice on the lower filter whereby the ice at the lower end of the vessel co-acts with the ice in the upper portion of the vessel 105 to maintain a uniform temperature and thereby prevent the entry of and ascendency of warm air upwardly into the vessel through the perforated bottom to counteract the downward current of air and whereby the constant downward current of air through the vessel is maintained, said filters being impregnated with an odorless and germ killing substance whereby to prevent entry of germs into the vessel upon melting 110 115 120 125 130

- of the ice and consequent lowering of temperature in the vessel and to prevent discharge of air contaminated with the odor of the nutriments.
5. 9. A refrigerator for preserving nutriment and other goods comprising a container having a perforated bottom and fitted at its upper end with an ice cooled filter and having on its bottom an ice cooled filter, the upper filter being cooled by water dropping from ice in the upper portion of the container supported above the filter, a grate on the lower filter on which ice is supported in the lower portion of the container, the ice at the bottom of the container preventing entry of warm air through the perforated bottom and providing for a uniform temperature within the container and thereby preventing hindrance to the down-
ward current of cooled air from the top to 20 and through the perforated bottom of the container and whereby a constant downward current of air through the container is maintained, said filters being impregnated with an odorless and germ killing substance 25 whereby to prevent entry of germs into the container upon melting of the ice and consequent lowering of temperature in the container and to prevent discharge of air contaminated with the odor of nutriments. 30
- In testimony whereof I have signed my name to this specification in the presence of two subscribing witnesses.
